(57) **CLAIM**

The ornamental design for a X-ray residual stress measuring instrument, as shown and described.

DESCRIPTION

FIG. 1 is a front elevational view of a X-ray residual stress measuring instrument showing our new design;

FIG. 2 is a top plan view thereof;

FIG. 3 is a bottom plan view therefore;

FIG. 4 is a rear elevational view thereof;

FIG. 5 is a left side elevational view thereof;

FIG. 6 is a right side elevational view thereof;

FIG. 7 is a cross-sectional view thereof, taken along the line 7-7 of FIG. 1;

FIG. 8 is a cross-sectional view thereof, taken along the line 8-8 of FIG. 2;

FIG. 9 is a perspective view thereof; and,

FIG. 10 is a perspective view thereof.
